UNITED STATES PATENT OFFICE.

ALFRED S. TOPPING, OF HART, MICHIGAN.

RAILROAD-TIE.

No. 909,713.

Specification of Letters Patent.

Patented Jan. 12, 1909.

Application filed July 13, 1908. Serial No. 443,194.

To all whom it may concern:

Be it known that I, ALFRED S. TOPPING, a citizen of the United States, residing at Hart, in the county of Oceana and State of Michigan, have invented certain new and useful Improvements in Railroad-Ties, and I do declare the following to be a full, clear, and exact description of the invention, such as will enable others skilled in the art to 10 which it appertains to make and use the same.

This invention relates to improvements in metallic railroad ties and fastening devices for securing railroad rails to said ties.

The object of the invention is to provide 15 simple and efficient means for securing a railroad rail to a metallic tie, said tie and fasteners being so constructed as to reliably fasten a rail to the tie without danger of its working loose.

With these and other objects in view, the invention consists of certain novel features of construction, combination and arrangement of parts, as will be more fully described and particularly pointed out in the 20 appended claims.

In the accompanying drawings, Figure 1 represents a top plan view partly in horizontal section of a tie having a rail fastened thereto, and constructed in accordance with 30 this invention. Fig. 2 is a view partly in side elevation and partly in section taken on the line 2—2 of Fig. 1. Fig. 3 is a perspective view taken from one side of a metallic tie constructed in accordance with 35 this invention. Fig. 4 is a transverse section taken on the line 4—4 of Fig. 1.

In the embodiment illustrated a tie 1 is shown, made of steel, iron or other suitable 10 metal and which may be wrought, cast or otherwise constructed. This tie is preferably hollow and is open on its lower side and at its ends, and the side walls 2 thereof are provided at their lower edges with outwardly extending base flanges 3, which form broadened lower surfaces to bear on the ground and which are provided with apertures or notches 3', to receive spikes (not shown), for securing the ties to culverts, 15 bridges and the like.

The side walls 2 of the tie are provided at their ends with outwardly extending flanges 4, the outer sides of which are at a slight distance from the ends of the base flanges.

5 The ends of the tie may be closed by means

of plates 5, which are preferably rectangular in form and of an appropriate size to bear on the base flanges and against the vertical outwardly extending flanges 4 of the tie, and the ends of said plates are bent to 60 provide flanges 6, to bear against the inner sides of said flanges 4 and with grooves 7, to receive said flanges 4, so that said end plates 5, may be placed on the ends of the tie by merely placing them downwardly thereon to cause them to engage the flanges 4 at the ends of the tie. It will be understood that said plates may be detached from said ends of the tie by raising them to cause them to clear the flanges 4. When placing 70 a tie one of the plates 5 must be removed and the tie filled with earth or sand and tamped so as to ballast the tie and firmly hold the same in place on the road bed, and the end plate is then secured in place. 75

To remove the tie, one of the end plates is first removed and the tie can then be readily moved endwise without lifting the same and cause it to readily disengage from the ridge of earth formed by the tamping 80 of the earth in the tie, as will be understood. In the upper face of the tie are longitudinally spaced recesses as 11, which extend transversely across the entire width of the tie, and in which are disposed wooden 85 blocks or plates 12, on which the rails as b bear, said blocks or plates forming cushions between the rails and the tie, and are designed to relieve the ties from the concussion caused by the passing of trains, and 90 they also enable the ties to yield somewhat as the trains pass over them.

Communicating with the transverse recesses 11 at opposite sides of the face of the tie are two depressions or recesses as 11^a, 95 formed over and adjacent to the side members or walls of the tie for a purpose to be described.

Rail securing devices 13 are provided for use in connection with this improved tie 100 and each of which has a part 14 constructed to bear on one side of the base of the rail b, and a vertical flange 15 to enter one of said recesses 11^a and bear against the shoulder 16, formed by the end of said recess. Said 105 rail securing devices are preferably made of iron or steel and are provided with openings for the reception of bolts as 17, which are employed to secure said devices on the tie. Each of said bolts 17 has a squared or angu- 110

lar portion near its head which engages a similarly shaped opening in the depressed portion of the tie forming one of the recesses as 11^a to prevent said bolt from turning, and the nuts 20 of said bolts are screwed on the upper end thereof above said devices 13. These bolts 17 are preferably split longitudinally at their screw threaded ends, and after the nuts have been screwed on wedges 10 as 21, having heads as 22, are inserted in the split ends of the bolts to serve as nut locks, and when it is desired to remove the nut the wedge is first tapped gently on either side a few times and then the wedge may be 15 removed with a pair of pincers.

For use on curves one of the fastening members 13 is provided with a vertical extension 23, which is adapted to fit under the thread of the rail *b* and perform the double 20 function of a rail brace and fastener therefor.

To enable the bolt 17 to be placed in position to extend through the recessed portion of the upper side of the tie the opening 18 through which the squared or angular portions of the bolt extend are elongated to form oblique slots, which extend toward the rail and are provided at their outer ends with openings 19 of sufficient size to clear the heads of the bolts, and which form enlargements on the outer portions of said slots. These slots 18 facilitate the placing of the rail securing devices on the tie and in engagement with the rails, and also facilitate the removal of such devices when it is desired to remove or take up the rails. The inner ends of the slots 18 terminate a sufficient distance from the side walls 2 of the tie to permit the heads to lie within the walls.

By arranging the flanges 15 of the rail 40 securing devices 13 in the ends of the recesses 11^a and against the shoulders 16 permitting the ends of said recesses to pass the bolts 17 therethrough the devices are effectively prevented from moving outwardly or 45 upwardly, and hence serve to securely fasten the rails on the ties and prevent said rails from spreading.

In the use of these devices when the ties have been placed in position the rails *b* are 50 arranged on the wooden blocks 12 disposed in the depressions 11 and the bolts 17 are inserted in the slots 18 by passing their heads through the enlarged opening 19 of said slots and then moving the bolt through 55 the slots 18 until they reach the desired position in the recesses 11^a. The bolt 17 is then passed through the aperture in the member 14 of the fastener 13 and the lug 15 of the fastener is inserted in the recesses 11^a against 60 the shoulder 16, formed at the end of said recess. The recesses 11^a in which said fasteners are mounted being arranged over and adjacent to the side walls 2 of the tie, said walls serve to reinforce and brace the 65 fasteners, and danger of bending of the tie

at the point of connection with the rail is avoided and the fasteners are less affected by the vibrations produced by passing trains than if they were arranged nearer the center of the tie. By arranging the recesses 11^a at 70 the outer edges of the upper face of the tie one shoulder 24 only is provided, the recesses being open at their outer walls.

From the foregoing description, taken in connection with the accompanying drawings, the construction and operation of the invention will be readily understood without requiring a more extended explanation.

Various changes in the form, proportion and the minor details of construction may be 80 resorted to without departing from the principle or sacrificing any of the advantages of this invention as defined in the appended claims.

I claim as my invention:—

1. A metallic railroad tie having recesses arranged at points on opposite sides of the rail at the side edges of the tie, in combination with rail fastening devices having flanges to bear on the base of the rail and flanges to enter said recesses in the tie, bolts detachably securing said devices to said tie, said tie being provided with slots lying at an oblique angle to the plane of the rails for the reception of said bolts, said slots being 95 enlarged at their outer ends to admit the heads of said bolts, and the smaller end extending toward the rail and terminating in said recesses.

2. A metallic railroad tie having longitudinally spaced depressions extending transversely across the width thereof to receive the rails and recesses in the upper face of the tie adjacent said depressions at the side edges of said tie and extending over the 105 side members of said tie, in combination with rail fastening devices adapted to bear on the base of the rail and having flanges to enter said recesses in the tie, and means for securing said fasteners in operative position.

3. A hollow metallic railroad tie having laterally extending base flanges provided with spaced recesses, said tie having rail receiving depressions extending transversely 115 across its upper face, with recesses on opposite sides thereof adjacent thereto at the side edges of said tie, in combination with rail fastening devices constructed to engage the base of the rail and to enter said recesses, 120 and means for securing said fastening devices in operative position.

4. A metallic railroad tie having a depression extending transversely across the width thereof to receive a rail, said tie having recesses in its upper face adjacent said depression at the side edges of said tie and extending over the side members thereof, in combination with rail fastening devices adapted to bear on the base of the rail and having 130

flanges to enter said recesses in the tie, one of said fastening devices being provided with an upright brace extension for engagement with the tread of the rail, and means for securing said fasteners in operative position.

In testimony whereof I have hereunto set

my hand in presence of two subscribing witnesses.

ALFRED S. TOPPING.
